Attorney

UNITED STATES PATENT OFFICE.

EDWARD M. CRAIG, OF CHARLESTON, WEST VIRGINIA.

WINDOW-SCREEN.

1,228,536.

Specification of Letters Patent.

Patented June 5, 1917.

Application filed October 3, 1916. Serial No. 123,535.

To all whom it may concern:

Be it known that I, EDWARD M. CRAIG, a citizen of the United States, residing at Charleston, in the county of Kanawha and 5 State of West Virginia, have invented certain new and useful Improvements in Window-Screens, of which the following is a specification, reference being had to the accompanying drawings.

10 This invention relates to an improved window screen and has for its primary object to provide simple and serviceable means for screening the entire window opening, which may be readily made and applied in 15 position without requiring the services of a skilled mechanic.

It is another and more particular object of the invention to provide a screen for the above purpose embodying a rectangular 20 frame, the opening of which is entirely covered with a reticulated fabric, and suitable means for removably securing the screen frame in place exteriorly of the window sashes so that said sashes may be freely 25 moved to their open or closed positions.

It is also a further general object of my invention to improve and simplify devices of the above character whereby the same are rendered very serviceable and convenient in 30 practical use and capable of manufacture at relatively small cost.

With the above and other objects in view, my invention consists in the novel features of construction, combination and arrangement of parts to be hereinafter more fully described, claimed and illustrated in the 35 accompanying drawings, in which,

Figure 1 is a view in perspective illustrating a screen arranged in accordance with 40 the embodiment of my invention.

Fig. 2 is a perspective view of still another form of the device;

Fig. 3 is a horizontal sectional view of the latter form and

45 Fig. 4 is a detail section taken on the line 7-7 of Fig. 3, illustrating the mounting of the removable screen sections.

In Fig. 1 of the drawings, I have shown the two screen sections 13 each occupying 50 one-half of the frame opening, connected by a horizontal hinge joint 14. Each of these sections of the screen is adapted to be connected along its vertical edges by means of detachable fastenings 15 to the frame of the window. Upon the window sill, a suitable 55 catch member, indicated at 16, is mounted to

operatively engage the lower edge of the lower screen section 13 and hold the same in its closed position.

Figs. 2 and 3 of the drawings illustrate a 60 mounting and arrangement of a plurality of relatively movable screen sections, and I have herein shown two upper screen sections 17 each occupying one-quarter of the frame A fitting within the window opening 65 and mounted upon suitable horizontal pivots indicated at 18, for vertical swinging or turning movement. The lower half of the frame A is adapted to be closed by two screen sections 19, each of which is pivoted 70 or hingedly mounted at one of its edges, as at 20, for horizontal swinging movement. These several screen sections are likewise provided with suitable latches, whereby they may be conveniently held in closed position. 75 The pivots 18 and 20 are preferably of such construction as to permit of the easy and quick removal of any one or more of the screen sections. It is preferred that each of the pivots 18 coöperate with a vertical 80 member of the frame A as particularly illustrated in Fig. 7 and wherein the pivot 18 is engaged with the upwardly inclined open-end groove 21. Pivots engaged with said vertical member of the frame A above 85 the slot 21 is the dog 22 adapted to engage the upper portion of the pivot 18 and thereby effectively maintain the same in applied position within the groove 21. It is also preferred that the dog 22 be provided with 90 an extension 23 adapted to contact with the pivot 18 and of a length to extend substantially entirely across the groove 21 when the dog 22 is engaged with the pivot 18. The frame A is adapted to be locked within the 95 window opening in any desired manner as indicated at 24. This latter form of the device is especially desirable for household use as it will permit an awning cord or rope being readily reached from the interior of the 100 house by simply swinging any one of the screen sections to open position, thus avoiding the necessity of removing the entire frame.

From the foregoing description, taken in 105 connection with the accompanying drawings, the construction, manner of operation and several advantages of the several described embodiments of the invention will be clearly and fully understood. It will be 110 seen that I have devised an inexpensive, convenient and serviceable window screen

which may be easily constructed and arranged in place within the window frame by one of ordinary skill. The screens can, of course, be constructed in various sizes and 5 the screen fabric may be of any desired mesh. Where the screen is to be employed for purposes of safety, it is to be understood that the screen or grading will be of relatively heavy material and a greater number of the fastening elements may be provided. 10 The invention is also susceptible of many other obvious modifications in the form, proportion and arrangement of its several parts and I, therefore, reserve the 15 privilege of adopting all such legitimate changes as may be fairly embodied within the spirit and scope of the invention as claimed.

Having thus fully described my invention, 20 what I desire to claim and secure by Letters Patent is:—

1. A device of the character described comprising a frame adapted to be positioned within an opening, opposed edges of 25 said frame being provided with open-end grooves, a screen section provided with pivot

members insertible within said grooves, and dogs pivotally engaged with the frame and arranged for contact with said pivot members for holding the screen section within 30 the frame.

2. A device of the character described comprising a frame adapted to be positioned within an opening, opposed edges of said frame being provided with open-end 35 grooves, a screen section provided with pivot members insertible within said grooves, and dogs pivotally engaged with the frame and arranged for contact with said pivot members for holding the screen section 40 within the frame, each of said dogs being provided with an extension arranged for contact with a pivot member and of a length to substantially intersect a groove when the dog is operatively engaged with a pivot 45 member.

In testimony whereof I hereunto affix my signature in the presence of two witnesses.

EDWARD M. CRAIG.
